MAILING FOLDER

Harold J. Hayden, St. Albans, N. Y., assignor to
 Empire Corrugated Container Corp., Brooklyn,
 N. Y.

Application December 16, 1938, Serial No. 246,087

6 Claims. (Cl. 229—30)

This invention relates to improvements in mailing folders of the envelope type and more particularly to a mailing folder constructed of corrugated sheet material.

One of the important features of the invention resides in a mailing carton or folder for relatively heavy magazines, books, or like flat articles, into which such articles are adapted to be packaged for shipment through the mail or other carrier, without fear of mutilation of the folder contents during handling and shipment.

Another feature of the invention is to provide a mailing folder which is formed of a single blank of stiff corrugated paper stock which is cut, scored, folded, and sealed in a novel manner to provide a strong, rigid, and inexpensive container for the safe shipment of flat articles.

A further feature of the invention is the provision of a mailing envelope folder constructed of relatively heavy stock material such as corrugated paper board in which certain opposed infolded flaps interlock and are disposed on the same plane to serve the two fold purpose of bracing the folder against lateral strains, and for reducing the thickness of the infolded flaps to a minimum.

A still further feature of the invention is the provision of a mailing envelope folder in which the infolded overlapping closure flaps are securely held together by metal stitching in a novel manner not to penetrate to the inside of the folder which might cause injury to the contents of the folder, nor which is likely to cause injury to the hand during handling of the folder in shipment.

Other important features of the invention will be apparent as the specification is read in conjunction with the accompanying drawing, in which:

Figure 1 is a plan view of the blank from which the mailing folder is constructed.

Figure 2 is a perspective view of the folder in partially folded position.

Figure 3 is a perspective view of the folder in complete folded and sealed condition.

Figure 4 is an enlarged vertical transverse sectional view on the line 4—4 of Figure 3.

Figure 5 is an enlarged vertical longitudinal sectional view on the line 5—5 of Figure 3.

Referring to the drawing by reference characters, the letter A designates the flat blank of stiff foldable material which is cut, scored, and folded to produce my improved mailing folder. The blank A is cut from a substantially rectangular shaped piece of stock material shown in dot and dash lines and designated B. The stock material B is preferably corrugated paper sheet material and the corrugations of the sheet material are disposed parallel to two of the opposite sides of the sheet B so that when the blank A is folded

into envelope position, the corrugations run oblique to the several walls and flaps which make up the folder. By cutting the blank A from a piece of corrugated stock material B in the manner above mentioned, I am able to increase the strength of the walls of the folder and reduce the waste of stock material to a minimum.

The blank A includes a front wall 10 of rectangular configuration in plan and formed integral with the ends of the front wall 10, are relatively narrow end walls 11 and 12 which are foldable to a position at right angle to the front wall 10 on the transverse score lines 13 and 14 respectively. Formed integral with the end walls 11 and 12 are inner rear wall flaps 15 and 16, the same being foldable inwardly at right angle to the respective end walls 11 and 12 on the transverse score lines 17 and 18 respectively. The inner rear wall flaps 15 and 16 are substantially triangular shaped and the apex portion of the flap 16 is provided with a V-shaped notch 19 to receive the apex portion 21 of the flap 15 when the flaps 15 and 16 are folded inwardly over the front wall 10 as best illustrated in Figure 2 of the drawing. Formed integral with opposite sides of the flaps 15 and 16 and terminating in alignment with the score lines 17 and 18, are corner flaps 20 which are foldable inwardly on the score lines 21, which score lines are in alignment with the free ends of the end walls 11 and 12. The corner flaps 20 are of a width approximating the height of the end walls 11 and 12.

Formed integral with opposite sides of the front wall 10 along the score lines 22—22, are opposite side walls 23—23 and formed integral with the side walls 23—23 are outer rear wall flaps 24—24 foldable inwardly at right angle to the side walls 23—23 on the longitudinal score lines 25—25. The outer rear flaps 24—24 are substantially triangular shaped and have their apex portions rounded as at 26. The outer flaps 24—24 are of a width to enable the apex portions thereof to overlap each other and to overlap the meeting edges of the inner rear flaps 15 and 16.

Assume that it is desired to package a relatively thick and heavy magazine as shown in dotted lines at M in Figure 2, and that the inner side of the blank A is face up in Figure 1. The operator places the magazine M against the inner side of the front wall 10 and folds the end walls 11 and 12 upwardly against opposite ends of the magazine on the fold lines 13 and 14, after which the inner rear flaps 15 and 16 are folded inwardly on the lines 17 and 18 respectively so as to lie flat against the upwardly facing side of the magazine M. When the flaps 15 and 16 are folded inwardly, the apex portion 21 of the flap 15 interfits into the V-shaped notch 19 of the flap 16 as best illustrated in Figure 2. The corner flaps 20 are next folded inwardly so as to

reinforce the corners of the folder and protect the corner edges of the magazine from becoming exposed. The operator next folds the side walls 23-23 on the score lines 22-22 and then proceeds to fold the outer rear flaps 24-24 inwardly on the score lines 25-25 so that the apex portion of one of the outer rear flaps 24 overlaps the apex portion of the other flap 24. In addition to overlapping each other, the apex portions of the flaps 24-24 overlie and conceal the interfitting apex portions of the inner rear flaps 15 and 16. The blank is now completely folded and is ready for sealing, and whereas various types of sealing means may be resorted to, I have illustrated a substantially U-shaped metal staple 28 which has its leg portions passing through the overlapping flaps 24-24 and with the terminal ends of the leg portions of the staple bent inwardly and embedded in the thickness of the apex portion of the inner rear wall flaps 15. It is possible to use such type of fastening in relatively thick corrugated material and there are stapling machines now available for applying fastening staples in the manner above set forth.

From the foregoing description, it will be seen that I have provided a relatively simple and inexpensive mailing folder which is strong and rigid to protect the contents of the folder from injury during the rough handling to which mailing folders are subjected in transit through the mails.

While I have shown and described what I consider to be the most practical embodiment of my invention, I wish it to be understood that certain changes and alterations as come within the scope of the appended claims may be resorted to if desired.

Having thus described the invention, what I claim as new and desire to secure by Letters Patent of the United States, is:

1. A mailing folder comprising an envelope body having a front wall, and inner and outer pairs of opposed inwardly foldable flaps constituting a rear wall, interfitting means between the inner pair of flaps to brace the same against lateral strain and to enable said inner flaps to assume a common plane throughout their entire area, the outer flaps overlapping each other and said inner flaps, and means securing said outer flaps in lapped relation to one of the pair of inner flaps.

2. A mailing folder comprising an envelope body having a front wall, and inner and outer pairs of opposed inwardly foldable flaps coacting to provide a rear wall, one of the flaps of the inner pair having a notch provided in a free edge thereof, a complementary interfitting element provided on the free edge of the other inner flap and snugly interfitting into said notch whereby said inner flaps are disposed on the same plane throughout their entire area and braced against lateral strain, the outer pair of flaps overlapping each other and said inner flaps, and securing means for fastening said outer flaps in overlapped relation to one of the pair of inner flaps.

3. A mailing folder comprising an envelope body constructed of a single blank of relatively stiff thick paper material which is cut, scored, and folded to provide a rectangular shaped front wall, side walls, inner and outer pairs of flaps folded inwardly from said side walls and coacting to provide a rear wall, said inner folded flaps

terminating in edge to edge relation to lie in the same plane, interfitting means between the adjacent edges of said inner flaps to brace said inner flaps against lateral strain, said outer pair of flaps having portions overlapping each other and said inner flaps, a metal staple passing through said overlapping outer flaps and embedded in the thickness of one of said inner flaps to secure said outer flaps to one of the inner flaps in overlapped relation.

4. A mailing folder comprising an envelope body constructed of a single blank of relatively stiff paper material, cut, scored, and folded to provide a rectangular shaped front wall, side walls, inner and outer pairs of opposed flaps folded inwardly from said side walls and being substantially parallel to said front wall, said inner walls lying in the same plane, corner flaps integral with the opposed sides of said inner flaps and being folded inwardly at right angle to said inner flaps and fitting against adjacent side walls to enclose the corners of said envelope body, said outer flaps being disposed in lapped relation with each other and with respect to said inner flaps, and fastening means for securing the outer flaps to one of the inner flaps in overlapping relation.

5. A mailing container for magazines or other like flat articles comprising a single blank of corrugated paper board which is cut, scored, and folded to provide a rectangular shaped front wall, opposed end walls, opposed side walls, substantially triangular shaped inner rear wall flaps integral with said end walls, the apex portion of one of said rear wall flaps having a V-shaped notch therein, said rear wall flaps being folded inwardly with the V-shaped notch of the one rear wall flap snugly receiving the apex portion of the other rear wall flap whereby said rear wall flaps are interlocked to resist lateral strain and disposed in the same plane throughout their entire areas, and a pair of outer rear wall flaps integral with the side walls and folded inwardly over the inner rear wall flaps and cooperating therewith to entirely close the rear of the container.

6. A mailing container for magazines or other like flat articles comprising a single blank of corrugated paper board which is cut, scored, and folded to provide a rectangular shaped front wall, opposed end walls, opposed side walls, substantially triangular shaped inner rear wall flaps integral with said end walls, the apex portion of one of said rear wall flaps having a V-shaped notch therein, said rear wall flaps being folded inwardly with the V-shaped notch of the one rear wall flap snugly receiving the apex portion of the other rear wall flap whereby said rear wall flaps are interlocked to resist lateral strain and disposed in the same plane throughout their entire areas, a pair of substantially triangular shaped outer rear wall flaps integral with the respective side walls and folded inwardly with their apex portions overlapping each other and portions thereof overlapping the inner rear wall flaps and cooperating therewith to entirely close the rear of the container, and a metal staple fastener passing through the lapping portions of said outer rear wall flaps and into the un-notched inner rear wall flap to secure the same in closed position.

HAROLD J. HAYDEN.
